PORTABLE HYDROCARBON FURNACE

Thomas Keeler, Minneapolis, Minn., assignor, by
mesne assignments, to Cedarberg Manufacturing Company Inc., Minneapolis, Minn., a corporation of Minnesota

Application June 11, 1945, Serial No. 598,746

12 Claims. (Cl. 158—32)

1

My invention relates to improvements in liquid fuel burning furnaces and has for an object thereof to provide a portable utility furnace of compact, durable and inexpensive construction capable of burning liquid fuels efficiently and quietly in flames graduated between high and low extremes.

Another object of the invention is to supply a furnace of the present nature especially adapted in the interests of safety and economy, to generate gas from kerosene and other low grade fuels and to burn the same over long periods of time, without becoming fouled by carbon deposits and without the burning-out of the furnace parts.

A further object of the invention is to provide a device, as above, in which the initial generation of gas, through the medium of a priming liquid, is effected quickly and with ease and in which the continued normal generation of gas is efficiently accomplished throughout the entire range of graduation of the burner flame.

Other objects of the invention reside in the novel combination and arrangement of parts and in the details of construction hereinafter illustrated and/or described.

In the drawings, Fig. 1 is an elevational view and Fig. 2 is a plan view illustrating a furnace in embodiment of my invention, portions of the structure portrayed in both of said views being broken away to reveal otherwise hidden parts; Fig. 3 is an enlarged vertical sectional view in detail taken as on the line 3—3 of Fig. 2; Fig. 4 is an enlarged sectional view in detail taken as on the line 4—4 of Fig. 2 and illustrating the valved fitting in the liquid-fuel line between the pressure tank and the generating ring, and Fig. 5 is a view, similar to Fig. 4, taken as on the line 5—5 of Fig. 2 and illustrating the valved fitting in the gas line taking off from the generating ring.

Reference being had to the accompanying drawings, wherein similar parts are designated by similar reference characters throughout the several views, it will be seen that the illustrated embodiment of my invention includes a tank 10 forming the base of the portable structure.

In the top of this tank 10 is a filler-opening (not shown) normally closed by a filler-cap 11 in which is embodied an air admission valve 12.

Rising from the top of the tank and spaced apart about the axis thereof are a number of legs 13, each consisting of an upright reach 14 having inturned flanges 16, 15 at its upper and lower ends, respectively, the latter forming a foot

2

and the former forming a mounting upon which a portion of the burner rests.

- The burner, indicated in its entirety by the reference character X, includes a generating ring 5 A, a primary mixing member B and a secondary mixing member C. Forming a part of the secondary mixing member C is a tray 17 having lugs 18 extending radially outward therefrom. These lugs 18 rest on and are secured by bolts 19 to the mounting flanges 16 of the legs 13. Supported by said legs 13, the tray 17, in turn, supports the remaining parts of the burner. This tray 17 is centrally apertured, as at 20, and has an annularly upturned deflector-rim 21.
- 15 The generating ring A is annularly tubular, as well as axially tubular, and is preferably made of thin sheet metal formed to provide a thin chamber 22 between inner and outer concentric walls 23, 24. As shown, said walls 23, 24 are turned upon themselves at the upper edge of the ring A, the gap between the two walls at the lower edge of the ring being closed by welding material 25. Disposed axially upright, the generating ring A rests with its lower edge bearing upon the lugs 18 of the tray 17, the inner wall 23 of said ring A being spaced outwardly of the deflector-rim 21 of said tray to provide an annular air-admission port 26 between said ring and said tray.
- 20 30 A liquid-fuel supply line, leading from the interior of the tank 10 to the generating chamber 22 of the ring A, comprises an upright pipe 27 extending through the top of the tank, a valved fitting 28 (Fig. 4) at the upper end of said pipe 27 and a nipple 29 disposed laterally between said fitting and ring. The fitting 28 has a passageway therethrough consisting of a series of branches 30, 31 and 32, the branch 32 being formed to provide a seat for a needle-tip 33 on a valve-stem 34 threaded into said fitting 28 and supplied with a knob 35 for turning the same. The nipple 29 takes-off from the fitting 28 and extends through the outer wall 24 of the ring A to bring the nipple 29 into communication with the generating chamber 22 interiorly of said ring.
- 35 40 45 The gas line, leading from the generating ring A, consists of a horizontally disposed nipple 36 and a valved fitting 37 (Fig. 5) depending therefrom. Said nipple 36 is axially aligned with the nipple 29 diametrically of the generating ring A, the inner end of nipple 36 extending through the outer wall 24 of said ring to bring said nipple into communication with the generating chamber 22 within said ring. A passageway extending through the fitting 37 consists of a series of

branches 38, 39 and 40, the latter of which constitutes a horizontally directed outlet orifice formed to provide a seat for a needle-tip 41 on a valve-stem 42 threaded into said fitting and supplied with a knob 43 for turning the same.

The primary mixing member B includes a hollow body 44 open at the top thereof and providing a main mixing chamber 45, said body being integrally formed with a horizontally disposed mixing tube 46 leading into said chamber 45. At the upper portion of the body 44 of said mixing member B are a number of lugs 47 which are fastened by screws 48 to the tray 17. Said body 44 is thus positioned relative to the tray to bring the open-top of the mixing chamber 45 into registry with the aperture 20 in said tray 17. A gasket, as at 49, is interposed between said body and tray and the mixing tube 46 is axially aligned with the discharge orifice 40 of the gas supply fitting 37, the open end of said tube 46 being located adjacent to the said fitting 37 so that the influx of gas thereinto jetting from said orifice 40 will induce an accompanying influx of air into said tube. Within the tube 46 is a deflector-vane 50 which serves to create turbulence in the inflowing generated gas and air, thereby enhancing the mixture thereof. Rising from the outer extremity of the mixing tube 46 is a fork 51 which receives the nipple 36 between its branches 52. These branches secure the nipple 36 laterally relative to said fork 51 and a keeper-screw 53, threaded through one of the branches 52, prevents any unpremeditated lifting of said nipple relative to said fork.

In addition to the tray 17, the secondary mixing member C includes a circular cap 54 spaced above said tray, and further includes an annular plate 55 located flatwise between and vertically spaced from said cap and tray, the cap 54 and annular plate 55 being axially aligned with the tray 17 and with the body 44 of the primary mixing member B. An upright stay-bolt 56, headed at its upper end, extends downwardly through the center of the cap 54 and through the bottom of the body 44 of the primary mixing member B. The lower threaded end of this stay-bolt 56 extends through a main primer-pan 57 beneath said body 44 and is screwed into a nut 58 welded to said pan at the lower side thereof. Thus, said stay-bolt 56 functions to center the cap 54 and to hold it in place along with the annular plate 55 and primer-pan 57. Posts 59, disposed in holes in the annular plate 55 at circumferentially spaced localities, are upset at their upper portions and thus firmly wedged in place relative to said annular plate. The lower portion of each post 59 extends beneath the plate 55 and forms a foot 60 which rests upon the tray 17 and spaces said plate 55 thereabove. The upper portion of each post is formed with a shoulder 61 for supporting the cap 54 in vertically spaced relation above the annular plate 55. The upper extremity of each post 59 is reduced in diameter to form a pintle 62 which is received in a companion hole 63 formed in the cap 54. Thus, said posts 59 serve to space the annular plate 55 from the tray 17 and the cap 54 from said annular plate, and serve further to center said annular plate 55 relative to the cap 54. The annular plate 55 is struck from relatively thin stock and, thus formed, is susceptible of becoming warped to the detriment of uniformity in the spacing of the same relative to the tray 17 and cap 54. To prevent such warping of said annular plate 55, upstruck beads 64 are formed in the inner mar-

gin thereof and, paired with said upstruck beads 64, are downstruck beads 65 formed in the outer margin of said plate 55. The beads 64, 65 of each pair are aligned radially of the annular plate 55 on a radial line intersecting the axis of one of the posts 59. Thus, located relative to the posts 59, said beads 64, 65 add virtually no impedance thereto to the radially outward passage of the fuel mixture in a lower stratum between the tray 17 and annular plate 55 and in an upper stratum between said annular plate 55 and the cap 54.

The cap 54 has an annular flange 66 at the perimeter thereof extending upwardly to the level 15 of the upper edge of the generating ring A. This flange 66 is inwardly spaced at its extreme lower portion from the upper portion of the upturned deflector-rim 21 of the tray 17 and, throughout 20 its major portion, said flange 66 is inwardly spaced from the inner wall 23 of said generating ring A. Between the generating ring A at the outside and the cap-flange 66 at the inside, a flue-like burner mouth 67 is formed, the same opening at the top thereof at the level of the upper 25 per edges of said generating ring and cap-flange. The tray 17 opens upwardly about the cap 54 into the lower portion of the burner mouth 67 and likewise opening into said portion of said mouth 67 is the annular port 26 through which secondary air is admitted.

An auxiliary primer-pan 68 secured to the main primer-pan 57 underlies the fitting 37 and said pans 57, 68 are provided with wicks 69 to absorb primer fluid introduced thereto.

Various implement-supporting superstructures (not shown) to meet various special requirements in the use of the present device may be anchored to the tray-lugs 18 by the bolts 19 and a handle attached in suitable manner to any such superstructure may be employed in carrying the device from place to place.

In operation, priming fluid, such as alcohol, saturating the wicks 69 in the primer-pans 57, 68, is lighted and the needle-tip 33 on valve-stem 34 is turned back from its seat to permit liquid fuel, such as kerosene, to pass from the pressure tank 16 into the chamber 22 in the generating ring A. Heat from the burning priming fluid heats the burner parts, the liquid fuel in the then amply heated generating ring being converted into a gas which, flows to and out of the discharge orifice 40 upon the unseating of the needle-tip 41 on valve stem 42. Said gas, jetting from said orifice 40, enters the heated generating tube 46 and with it induces the influx of air into said tube 46. Turbulence of the generated gas and air within the tube 46 and chamber 45 of the primary mixing member B produces a relatively raw fuel mixture which passes into the tray 17 of the secondary mixing member C. Reaching the tray 17, said mixture moves radially outward therein along both top and bottom of the annular plate 55 in a lower stratum next above the tray 17 and in an upper stratum next beneath the cap 54. The fuel mixture, stratified by the annular plate 55 of the secondary mixing member C, is further mixed and heated in said secondary mixing member C and, upon reaching the perimeter of the tray 17, is deflected upwardly into the burner mouth 67 by the upturned rim 21 of said tray. Meeting and commingling with the gas thus entering the burner mouth 67 is secondary air which also enters said mouth 67 through the annular port 26 between said rim 21 and the generating ring A. The admixture

of gas and secondary air, ascending in the flue-like mouth 67, is lighted to produce the burner flame. The heat from this flame keeps the burner parts hot after the priming liquid is consumed, thus enabling the mixing members B, C and the generating ring A to continue functioning in their respective capacities. The burner flame is graduated between high and low extremes by adjustment of the needle-tip 41 relative to its seat in the fitting 31. The generating ring A is sufficiently heated by this flame to convert kerosene into a gas even though the flame is low, the heating of said generating ring, in such case, being accomplished, in substantial part, by radiation from the tray 21 and flanged cap 54 of the secondary mixing member C. The production of a high flame in the burner is attended with a relatively strong upflow of secondary air through the port 26, the outer boundary of which is formed by the generating ring A. This voluminous upflow of air along the inner face of the generating ring A protects said ring against excessive heating that would tend to burn it out and keeps said generating ring from being so highly heated as to cause surging in the process of conversion therein of the liquid fuel into a gas.

From the foregoing, it will be seen that my improved, compact furnace, though of simple and relatively inexpensive construction, is capable of long and efficient operation even though the fuel used is of low grade. The uses to which the furnace may be put are manifold. Owing to the safety factor involved and the ability of my furnace quietly to produce flames throughout a wide range between high and low extremes from economical low-grade fuel, said furnace may be advantageously employed in the dairy, on the farm, in the home and, likewise, may be used by plumbers, sheet-metal workers and others in various pursuits, such as those engaged in the telephone and telegraph industries.

Changes in the specific form of my invention, as herein described, may be made within the scope of what is claimed without departing from the spirit of my invention.

Having described my invention, what I claim as new and desire to protect by Letters Patent is:

1. In a furnace of the character described, a tank and a burner, the tank being adapted to contain liquid fuel together with air under pressure for expelling such fuel from the tank, legs extending upwardly from said tank, said burner consisting of a generating ring and a primary and secondary mixing members, said secondary member including a circular tray, an annular plate and a circular cap, all vertically axially aligned, said tray being supported on said legs and formed with a central aperture therein, said annular plate being supported on and spaced flatwise above said tray to form a lower passageway, said cap being supported on and spaced above said annular plate to form an upper passageway, both of said passageways opening radially outward toward the perimeter of said tray, said primary mixing member including a body depending from said tray and having a mixing chamber therein opening upwardly into said tray through its central aperture, said primary member further including a mixing tube branching from said body and leading to the chamber therein, said generating ring being a flat-walled structure of annularly tubular formation disposed in axially upright position encircling said tray and cap, conduit means for conducting liquid fuel from the tank to the interior of the generat-

ing ring, other conduit means for conducting gas from the generating ring and discharging it into said mixing tube in a manner to induce the influx of air thereinto along with said gas, said tray having an upturned rim at the perimeter thereof to deflect upwardly the gases issuing from said passageways above and beneath said annular plate, said upturned rim being spaced inwardly from the generating ring to provide an air ingress port between tray and ring, said cap and tray forming the inner confine and said generating ring forming the outer confine of an annular flue-like burner-mouth which is fed from beneath by the gas upwardly deflected from said rim and by secondary air entering said port.

2. A portable furnace of the character described comprising a tank and a burner, the tank being adapted to contain liquid fuel together with air under pressure for expelling such fuel from the tank, said burner consisting of a generating ring and primary and secondary mixing members, said secondary member including a circular tray, an annular plate and a circular cap, all vertically aligned, said tray being supported on the tank and formed with a central aperture therein, said annular plate being supported on and spaced flatwise above said tray to form a lower passageway, said cap being supported on and spaced above said annular plate to form an upper passageway, both of said passageways opening radially outward toward the perimeter of said tray, said primary mixing member including a body depending from said tray and having a mixing chamber therein opening upwardly into said tray through its central aperture, said generating ring being a flat-walled structure of annularly tubular formation disposed in axially upright position encircling said tray and cap, conduit means for conducting liquid fuel from the tank to the interior of the generating ring, other conduit means for conducting gas from the generating ring and delivering it into said mixing chamber in a manner to induce the influx of air thereinto along with said gas, the rim of said tray being spaced inwardly from the generating ring to provide an air ingress port between tray and ring, said cap and tray forming the inner confine and said generating ring forming the outer confine of an annular flue-like burner-mouth which is fed from beneath by the gas issuing from said passageways above and beneath said annular plate and by secondary air entering said port.

3. In a furnace of the character described, a burner consisting of a generating ring and primary and secondary mixing members, said secondary member including a circular tray, an annular plate and a circular cap, all vertically aligned, said tray being formed with a central aperture therein, said annular plate being spaced flatwise above said tray to form a lower passageway and spaced beneath said cap to form an upper passageway, both passageways opening radially outward toward the perimeter of said tray, said primary mixing member including a body beneath said tray having a mixing chamber therein opening upwardly into the tray through its central aperture, said generating ring being a flat-walled structure of annularly tubular formation disposed in axially upright position encircling said tray and cap, conduit means for conducting liquid fuel to the interior of the generating ring, other conduit means for conducting gas from the generating ring and delivering it into said mixing chamber in a manner to induce the influx of air thereinto along with said gas,

said tray having an upturned rim at the perimeter thereof to deflect upwardly the gases issuing from said passageways above and beneath said annular plate, said upturned rim being spaced inwardly from the generating ring to provide an air ingress port between tray and ring, said cap and tray forming the inner confine and said generating ring forming the outer confine of an annular flue-like burner-mouth which is fed from beneath by the gas upwardly deflected from said rim and by secondary air entering said port.

4. In a furnace of the character described, a burner consisting of a generating ring and primary and secondary mixing members, said secondary member including a circular tray and a circular cap vertically axially aligned therewith, said tray being formed with a central aperture therein and said cap being spaced above said tray to form a passageway opening radially outward toward the perimeter of the tray, said primary mixing member including a body beneath said tray having a mixing chamber therein opening upwardly thereinto through its central aperture, said primary member further including a mixing tube branching from said body and leading to the chamber therein, said generating ring being a flat-walled structure of annularly tubular formation disposed in axially upright position encircling said tray and cap, conduit means for conducting liquid fuel from the tank to the interior of the generating ring, other conduit means for conducting gas from the generating ring and discharging it into said mixing tube in a manner to induce the influx of air thereinto along with said gas, a deflector-vane within said tube for inducing turbulence in the gas and air entering said tube, the rim of said tray being spaced inwardly from the generating ring to provide an air ingress port between tray and ring, said cap and tray at the inside and said generating ring at the outside forming an annular burner-mouth which is fed from beneath by the gas issuing from said passageway and by secondary air entering said port.

5. In a furnace of the character described, a burner consisting of a generating ring and a mixing member including a circular tray and a circular cap vertically axially aligned therewith, said tray being formed with a central aperture therein and said cap being spaced above said tray to form a passageway opening radially outward toward the perimeter of the tray, said generating ring being a flat-walled structure of annularly tubular formation disposed in axially upright position encircling said tray and cap, conduit means for conducting liquid fuel to the interior of the generating ring, other conduit means for conducting gas from the generating ring and delivering it, together with accompanying air, into said tray through the central aperture therein, the rim of said tray being spaced inwardly from the generating ring to provide an air ingress port between tray and ring, said cap and tray at the inside and said generating ring at the outside forming an annular burner-mouth which is fed from beneath by the gas issuing from said passageway and by secondary air entering said port.

6. In a furnace of the character described, a burner consisting of a generating ring and primary and secondary mixing members, said secondary member including a circular tray, an annular plate and a circular cap, all vertically axially aligned, said tray being formed with a central aperture therein, said annular plate being spaced flatwise above said tray to form a lower passageway and spaced beneath said cap to form

an upper passageway, both passageways opening radially outward toward the perimeter of said tray, said primary mixing member including a body beneath said tray having a mixing chamber therein opening upwardly into the tray through its central aperture, said generating ring being a flat-walled structure of annularly tubular formation disposed in axially upright position encircling said tray and cap, conduit means for conducting liquid to the interior of the generating ring, other conduit means for conducting gas from the generating ring and delivering it into said mixing chamber in a manner to induce the influx of air thereinto along with said gas, the rim of said tray being spaced inwardly from the generating ring to provide an air ingress port between tray and ring, said cap and tray at the inside and said generating ring at the outside forming an annular burner-mouth which is fed from beneath by the gas issuing from said passageways above and beneath said annular plate and by secondary air entering said port.

7. In a furnace of the character described, a burner consisting of a generating ring and a mixing member including a circular tray, an annular plate and a circular cap, all vertically axially aligned, said tray being formed with a central aperture therein, the annular plate having feet at one side thereof and shoulders at its opposite side, said feet resting on said tray and spacing said plate flatwise thereabove to form a lower passageway, said cap being supported on said shoulders and spaced above said annular plate to form an upper passageway, both of said passageways opening radially outward toward the perimeter of said tray, said generating ring being a flat-walled structure of annularly tubular formation encircling said tray and cap, conduit means for conducting liquid fuel to the interior of the generating ring, other conduit means for conducting gas from the generating ring and delivering it, together with accompanying air, into said tray through the central aperture therein, the rim of said tray being spaced inwardly from the generating ring to provide an air ingress port between tray and ring, said cap and tray at the inside and said generating ring at the outside forming an annular burner-mouth which is fed from beneath by the gas issuing from said passageways and by secondary air entering said port.

8. In a furnace of the character described, a burner consisting of a generating ring and primary and secondary mixing members, said secondary member including a circular tray formed with a central aperture therein, an annular plate and a circular cap, all vertically axially aligned, said tray having a mounting therefor, said annular plate having feet at one side thereof circumferentially spaced about the same and having shoulders at its opposite side also circumferentially spaced about said annular plate, said feet resting on said tray and spacing said plate flatwise thereabove to form a lower passageway, said cap being supported on said shoulders and spaced above said annular plate to form an upper passageway, both of said passageways opening radially outward toward the perimeter of said tray, said primary mixing member including a body beneath said tray and having a mixing chamber therein opening at the top thereof into said tray through its central aperture, a stay-bolt extending through the cap, plate, tray and body and holding said cap and plate in place relative to said tray, said generating ring being a flat-walled structure of annularly tubular

formation disposed in axially upright position encircling said tray and cap, conduit means for conducting liquid fuel to the interior of the generating ring, other conduit means for conducting gas from the generating ring and discharging it into said mixing chamber in a manner to induce the influx of air thereinto along with said gas, the rim of said tray being spaced inwardly from the generating ring to provide an air ingress port between tray and ring, said cap and tray at the inside and said generating ring at the outside forming an annular burner-mouth which is fed from beneath by the gas issuing from said passageways and by secondary air entering said port.

9. In a furnace of the character described, a burner consisting of a generating ring and a mixing member including a circular tray, a thin annular plate and a circular cap, all vertically axially aligned, said tray being formed with a central aperture therein, the annular plate having feet at one side thereof circumferentially spaced about the same and having shoulders at its opposite side in axial opposition thereto, the feet resting on said tray and spacing said plate flatwise thereabove to form a lower passageway, said cap being supported on said shoulders and spaced above said annular plate to form an upper passageway, both of said passageways opening radially outward toward the perimeter of said tray, said annular plate being formed with radially disposed reinforcing beads marginally thereof at positions aligned with the paired feet and shoulders thereon, said generating ring being a flat-walled structure of annularly tubular formation encircling said tray and cap, conduit means for conducting liquid fuel to the interior of the generating ring, other conduit means for conducting gas from the generating ring and delivering it, together with accompanying air, into said tray through the central aperture therein, the rim of said tray being spaced inwardly from the generating ring to provide an air ingress port between tray and ring, said cap and tray at the inside and said generating ring at the outside forming an annular burner-mouth which is fed from beneath by the gas issuing from said passageways and by secondary air entering said port.

10. In a furnace of the character described, a burner consisting of a generating ring and a mixing member including a circular tray, an annular plate and a circular cap, all vertically axially aligned, said tray being formed with a central aperture therein, the annular plate having feet at one side thereof and shoulders at its opposite side, said feet resting on said tray and spacing said plate flatwise thereabove to form a lower passageway, said cap being supported on said shoulders and spaced above said annular plate to form an upper passageway, both of said passageways opening radially outward toward the perimeter of said tray, means for centering the cap relative to the tray, means associated with said shoulders and cooperating with the cap to center the annular plate relative to said cap, said generating ring being a flat-walled structure of annularly tubular formation encircling said tray and cap, conduit means for conducting liquid fuel to the interior of the generating ring, other conduit means for conducting gas from the generat-

ing ring and delivering it, together with accompanying air, into said tray through the central aperture therein, the rim of said tray being spaced inwardly from the generating ring to provide an air ingress port between tray and ring, said cap and tray at the inside and said generating ring at the outside forming an annular burner-mouth which is fed from beneath by the gas issuing from said passageways and by secondary air entering said port.

11. A liquid fuel burner including a generating ring of annularly tubular formation, a mixing member having a terminal portion disposed within and spaced from said generating ring and forming in conjunction therewith an axially elongated annular burner-mouth having an annular discharge opening at one end thereof and an ingress opening for secondary air at the other end thereof, said mixing member having a passageway therein opening radially outward into the burner-mouth between said air ingress and discharge openings, conduit means for conducting liquid fuel to the interior of the generating ring, other conduit means for conducting gas from the generating ring and feeding it, together with accompanying primary air, into the passageway in said mixing member for delivery into said burner-mouth and for admixture therein with secondary air entering said air ingress opening.
12. A liquid fuel burner including a generating ring of annularly tubular formation having lengthwise flat inner and outer walls defining between them a uniformly thin axially elongated annular generating chamber, a mixing member having a terminal portion disposed within and spaced from the inner wall of said generating ring and forming in conjunction therewith an axially elongated annular burner-mouth axially coextensive with said generating chamber, said mixing member having a passageway therein annularly opening radially outward for the full discharge of fuel mixture therefrom into the burner-mouth intermediately of the same and of said axially elongated chamber in said generating ring, conduit means for conducting liquid fuel to said chamber in said generating ring, other conduit means for conducting gas from said chamber in said generating ring and feeding it, together with air admixed therewith, into said passageway in said mixing member.
